UNITED STATES PATENT OFFICE.

ROBERT FARNWORTH AND THOMAS TROUGHTON JACKSON, OF BOLTON, ENGLAND.

WARP-REGULATING MECHANISM FOR WEAVING-LOOMS.

1,116,400.

Specification of Letters Patent.

Patented Nov. 10, 1914.

Application filed September 28, 1912. Serial No. 722,964.

To all whom it may concern:

Be it known that we, ROBERT FARNWORTH and THOMAS TROUGHTON JACKSON, subjects of the King of Great Britain and Ireland, and residents of Bolton, in the county of Lancaster, England, cotton manufacturer and engineer, respectively, have invented certain new and useful Improvements in Warp-Regulating Mechanism for Weaving-
10 Looms, of which the following is a specification.

Our invention relates to improvements in warp-regulating mechanism for weaving looms, the object being to provide means
15 for giving a positive regulation of the warp beam so as to let off a given supply of the yarn and at the same time to hold all the ends tight, and while it is particularly adapted for small ware looms of the Poyser type it
20 is nevertheless applicable to looms for weaving wider fabrics.

Our invention consists essentially in the employment of a rising and falling ratchet pawl in conjunction with the pivoted vibration-
25 tor device used in the looms referred to and also in conjunction with the beam, containing a warp, a further feature of our invention being the provision of a pressure roller in connection with the warp beam made of
30 cork or sheathed with cork or similar resilient material.

Our invention will be fully described with reference to the accompanying drawings in which—

35 Figure 1 is a side elevation of so much of a Poyser tape loom as is necessary to illustrate the application of our invention, while Fig. 2 is an end elevation of same from the rear, partly in section.
40 In the aforesaid drawing *a* indicates the main forward framework of the loom, *b* the shuttle race, *c* the shuttle, *d* the guide comprising the dove tail block which fits in corresponding dove tail grooves, *e* the main
45 driving shaft, while the broken lines *f* indicate the warp, the shed of which is indicated as being open. All the parts referred to are of ordinary or usual construction. In
50 looms aforesaid a vibrating frame *g* is employed arranged transversely of the warp *f* and pivoted at *h* to the rear frame *i* of the loom in a position suitable and convenient, the upper portion carrying a rod or roller *j* over which the warp *f* passes while its
55 lower portion is controlled by a spring *k*, or springs, usually one spring, which is adapt-

ed to act in opposition to the tension of the warp *f* as the latter passes over the rod or roller *j* from the warp beam (which is not indicated) to the heddles. The spring has 60 its rearward end coupled to the center of the lower arm of the frame *g* while its forward end is, in turn, connected to a hooked rod *m* passing through the frame *a* threaded at its forward end and adjusted longitudinally by 65 a milled nut *n* or the like so that the tension on the warp can be adjusted as required. In connection with the vibrator frame *g* is a projecting arm *o* coupled to a slotted link *p* by the pin *o'* which is adapted to be 70 secured to the link at any predetermined point, pivotally depending from a rod *q* running alongside the loom frame, the forward end of this rod being connected to a pin *r* carried by a pivoted lever *s*, the lower 75 arm of said lever being provided with a bowl *t* engaging with a cam groove *u* formed in a cam *v* fixed on the usual cam or driving shaft *e*. The rearward end of the rod *q* has connected to it a pivoted pawl 80 *w*, the pivot pin *x* of which passes through the slot of an arm *y* pivoted on the shaft or beam *z* carrying or controlling the passage of the warp *f* over the vibrator *g* to the heddles. 85

One of the important features of our invention is to give the pawl *w* a rising and falling motion in accordance with the position of the vibrator *g* which latter, in turn, is regulated by the amount of yarn let off 90 from the beam by the pawl engaging with a ratchet wheel *2* on the end of the beam shaft *z*. When the vibrator *g* is in the normal position, as indicated by the full lines in the drawing, the ratchet pawl is in gear 95 with the ratchet wheel and should the yarn or warp *f* from any cause become tighter the upper end of the vibrator carrying the rod or roller *j* is pulled nearer to the heddles thus causing the arm *o* forming part of it 100 to move the pawl rod *q* and give the pawl a longer stroke so as to let off more yarn from the beam. Similarly if the warp yarn becomes slacker than normal, the vibrator *g* is pulled by the spring or springs *k* backward 105 and the ratchet pawl is then lifted clear of the teeth of the ratchet wheel, as indicated by broken lines and remains in such position until the normal working position is again reached. In this connection it should be understood that the projecting arm *o* is rigidly connected to the 110

slotted link p , the slot in which is only for the purpose of enabling the parts to be adjusted and set with relation to each other. The ratchet pawl is so pivoted on its pin 5 that it cannot fall beyond a certain point, that is to say, as to its ratchet end, so that it can always come into gear again at the proper position on the ratchet wheel. This is simply effected by providing it with a 10 projection 3 to engage with the rear face of the slotted arm connected with the pawl.

The various levers and links can be arranged in any convenient form and the ratchet pawl may be made to push or pull 15 so long as the objects referred to are accomplished.

A further feature of our invention in connection with the warp beam or shaft z is to provide a pressure roller 4 of cork or similar resilient material, the cork being suitably mounted on the roller. The cork is considerably cheaper than rubber which has been previously employed and is not affected by oil though it possesses the requisite 25 amount of resiliency for the purpose. The positive roller z , used in conjunction with the cork roller for the warp to pass between them when such roller z is not used directly as a warp beam, is made of iron in the usual 30 way and it is this roller which carries the ratchet wheel previously referred to. The cork roller or cork-covered roller is positively pressed against the warp passing between it and the roller z by mounting it in 35 a frame 5 provided with pivots 6 adapted to hook under bearings 7, a screw or screws 8 being carried at the rear end of the frame which may be adjusted against the framework of the loom so as to exert the required 40 pressure and yet enable the roller frame to be easily removed when required for passing the warp below it. Suitably-arranged guide rollers 9, or rods, are provided to guide the warp in the proper direction.

45 From the foregoing description it will be readily understood that the tension on the warp is automatically regulated.

What we claim as our invention and desire to secure by Letters Patent is:—

50 1. In a warp regulating mechanism, a main frame, a vibratory frame supported by the main frame, feed rollers disposed adjacent the vibratory frame, a horizontally disposed rod, a pawl carried by one end of 55 the rod, means carried by the feed rollers for coöperating with the pawl whereby movement of the rod will rotate the feed

rollers, means for reciprocating the rod, and connecting means between the rod and vibratory frame whereby movement of said vibratory frame will control the movement of the rod and the engagement of the pawl with the coöperating part on one of the feed rollers.

2. In a warp regulating mechanism, a 60 main frame, a vibratory frame pivotally supported on the main frame, warp feed rolls supported by the frame, a ratchet carried by one of the feed rolls, a rod supported by the frame, said rod having a pawl 65 on one end thereof adapted to mesh with the teeth of the ratchet, means disposed adjacent one end of the rod for operating the rod for causing the pawl to engage the teeth and move the same, and connecting means 70 between the rod and the vibratory frame, whereby movement of the said frame will control the engagement of the pawl with the ratchet.

3. In a warp regulating mechanism, a 75 main frame, warp feeding rollers on the frame, one of the rollers having a ratchet wheel, a horizontally disposed rod having a pawl on one end thereof, means for moving said rod connected thereto at its opposite end, a vibrator over which the warp 80 passes, connecting means between the vibrator and rod, whereby movement of the vibrator will control the movement of the rod and the engagement of the pawl with 85 the ratchet wheel.

4. In a warp regulating mechanism, a 90 main frame, warp feeding rollers on the frame, one of the rollers having a ratchet wheel, a vibrator over which the warp 95 passes, said vibrator having a laterally extending arm, a horizontally disposed rod, said rod having a depending link, means for forming a connection between the link and the arm, a pawl on one end of the rod, 100 said pawl adapted to coöperate with the ratchet wheel, whereby movement of the vibrator controls the movement of the rod and the engagement of the pawl with the ratchet.

105 In testimony whereof we have hereunto set our hands in the presence of two witnesses.

ROBERT FARNWORTH,
THOMAS TROUGHTON JACKSON.
